INVENTOR.

BY
Richard B. Duren..
ATTORNEY.

UNITED STATES PATENT OFFICE.

HARRY S. WHEATON, OF DALLAS, IOWA.

SANITARY TELEPHONE MOUTHPIECE.

1,404,413.

Specification of Letters Patent. Patented Jan. 24, 1922.

Application filed May 26, 1921. Serial No. 472,692.

To all whom it may concern:

Be it known that I, HARRY S. WHEATON, a citizen of the United States, residing at Dallas, in the county of Marion and State of Iowa, have invented certain new and useful Improvements in a Sanitary Telephone Mouthpiece, of which the following is a specification.

This invention relates to a sanitary telephone mouth-piece and has for its principal object to provide means combined with a mouth-piece for containing a disinfectant fluid.

Another object of the invention is to provide a device of this nature which is automatically opened and closed by means of the receiver hook usually found upon telephones now commonly in use.

A still further object of the invention is to generally improve upon sanitary mouth-pieces of this character by providing a device which will be of extremely simple, durable and inexpensive construction, one which is efficient and reliable in operation, and well adapted to the purpose for which it is designed.

With these and numerous other objects in view, the invention resides in certain novel features of construction, and the combination and arrangement of parts as will be hereinafter fully described and claimed.

In the drawing:

Figure 1 is a front elevational view of the device showing same attached to a telephone transmitter.

Figure 2 is a side elevational view thereof.

Figure 3 is a vertical section taken therethrough.

Figure 4 is a vertical section taken there-through at right angles to the view shown in Figure 3, and

Figure 5 is a rear elevational view of a transmitter of conventional construction showing my device attached thereto.

Referring to the drawing in detail it will be seen that 1 designates the telephone generally which is provided with the usual transmitter 2 which may be of any conventional construction and as usual is provided with a projection in the form of a flange 3 for receiving a mouth-piece. This conventional mouth-piece, however, is not used in the present instance. My device consists of a casing formed by the annular rim 4 to which is suitably attached a front plate and a rear plate 6. A flange 7 of circular con-

struction is attached to the front plate 5 so as to extend inwardly and to be spaced from the rim 4. Another rim of circular construction 8 is attached to the plate 6 and is slightly spaced from the flange 7. The plate 5 is provided with apertures 9 and an apertured disk 10 is mounted on the shaft 11 and keyed thereto and this shaft 11 is journaled in the plates 5 and 6 so that the disk 10 may be rotated whereby its apertures may register with the apertures 9. A similar disk 12 is keyed to the shaft 11 adjacent the rear plate 6 and is provided with apertures adapted to register with apertures 13 in this rear plate 6. A semi-circular slot 14 is provided in the front plate 5 and a pin 15 suitably carried on the plate 10 projects therethrough. A rod 16 is pivotally mounted on the pin 15 and is connected with a clamp 17 suitably mounted on the receiver hook 18. As shown clearly in Figure 1 when the receiver is removed from the hook 18 the rod 16 will be pushed upwardly so as to slightly move the pin 15 causing the apertures in the plates 10 and 12 to register with the apertures in the plates 5 and 6. A washer 19 is suitably attached to the outer side of the plate 6 by means of glue and receives the projection 3 of the transmitter 2. In order to hold the casing to the transmitter a plurality of lugs 20 are attached to the rear plate 6 for hingedly receiving the links 21 which are curved so as to conform with the rear periphery of the transmitter 2. A split ring 22 is received by the ends 23 of the links 21 and a nut and bolt 24 are associated with the ends of this ring 22 so as to hold the link 21 in firm engagement with the transmitter 2 thereby holding the casing tightly thereon. An aperture is provided in the rim 4 for receiving a closure plug 25. This plug 25 is adapted to be removed in order that a disinfectant liquid may be poured into the casing. This liquid will contact with the flange 7 and flow to the bottom of the casing. Should the casing at any time be turned upside down this flange 7 would cause the liquid to flow to the other end of the receptacle. Any liquid which might flow over the edge of this flange 7 would engage with the flange 8 and be transmitted to the bottom of the receptacle as will be readily understood. From the foregoing description, taken in connection with the accompanying drawings, the construction and operation of the device will be readily understood without a

more extended explanation. As numerous changes in form, proportion, and in the minor details of construction may be resorted to without departing from the spirit 5 of this invention, I do not wish to be limited to the construction herein shown other than as claimed.

Having thus described my invention what I claim as new is:

- 10 1. A mouth-piece of the class described comprising a casing having a front and rear wall provided with perforations, a pair of plates disposed within the casing adjacent the walls thereof and provided with apertures for registering with the apertures of the walls and means for rotating the plates so as to place their apertures in registry or non-registry with the apertures of the walls in the manner and for the purpose specified.
- 15 2. A mouth-piece of the class described comprising a casing including a front and a rear wall, a flange extending from the inner side of the front wall and another flange extending from the inner side of the rear wall so as to be spaced from the first mentioned flange, said walls provided with apertures, and a pair of rotatable plates mounted in the casing and provided with apertures 40 adapted to be placed in registry with the apertures of the walls in the manner and for the purpose specified, and means for attaching the casing to a transmitter of a telephone.
- 20 3. A mouth-piece of the class described comprising a casing including a front and a rear wall, a flange extending from the inner side of the front wall and another flange extending from the inner side of the rear wall so as to be spaced from the first mentioned

flange, said walls provided with apertures, and a pair of rotatable plates mounted in the casing and provided with apertures adapted to be placed in registry with the apertures of the walls in the manner and 30 for the purpose specified.

3. A mouth-piece of the class described comprising a casing including a front and a rear wall, a flange extending from the inner side of the front wall and another flange 35 extending from the inner side of the rear wall so as to be spaced from the first mentioned flange, said walls provided with apertures, and a pair of rotatable plates mounted in the casing and provided with apertures 40 adapted to be placed in registry with the apertures of the walls in the manner and for the purpose specified, and means for attaching the casing to a transmitter of a telephone.

In testimony whereof I affix my signature 45 in presence of two witnesses.

HARRY S. WHEATON.
